US00D798468S

(12) **United States Design Patent** (10) **Patent No.:** **US D798,468 S**
(45) **Date of Patent:** **** Sep. 26, 2017**

(54) **MIXER**

(71) Applicant: **Eppendorf AG**, Hamburg (DE)

(72) Inventor: **Norbert Koop**, Hamburg (DE)

(73) Assignee: **Eppendorf AG**, Hamburg (DE)

(**) Term: **14 Years**

(21) Appl. No.: **29/525,905**

(22) Filed: **May 4, 2015**

Related U.S. Application Data

(62) Division of application No. 29/446,595, filed on Feb. 26, 2013, now Pat. No. Des. 731,237.

(57) **CLAIM**

The ornamental design for a mixer, as shown and described.

DESCRIPTION

FIG. 1 is a front perspective view of a mixer showing the new design;

FIG. 2 is a top plan view thereof;

FIG. 3 is a left side view thereof; and

FIG. 4 is a right side view thereof.

FIG. 5 is a front perspective view of the mixer shown in FIG. 1 with a retainer element affixed to the top of the mixer.

FIG. 6 is a front perspective view of the mixer shown in the above Figures with a top protective cover;

FIG. 7 is a top plan view of the mixer illustrated in FIG. 6;

FIG. 8 is a left side view thereof; and,

FIG. 9 is a right side view thereof.

In the drawings, the broken lines are for the purpose of illustrating environment only and form no part of the claimed design.

1 Claim, 9 Drawing Sheets
